CLAIM

We claim the ornamental design for two-step heavy-duty stepladder, as shown and described.

DESCRIPTION

FIG. 1 is a perspective view of a two-step heavy-duty stepladder showing our design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines in the drawings are included for the purpose of illustrating portions of the two-step heavy-duty ladder and form no part of the claimed design.
